UNITED STATES PATENT OFFICE

2,524,101

CIRCUIT INTERRUPTING DEVICE

Ralph H. Earle, Wauwatosa, Wis., assignor to
 McGraw Electric Company, a corporation of
 Delaware

Application September 10, 1945, Serial No. 615,365

6 Claims. (Cl. 200—123)

1

This invention relates to improvements in a circuit interrupting device for protective apparatus in electric distribution circuits.

Protective apparatus in common use on electric distribution lines comprises a so-called valve type lightning arrester including an air gap and silicon carbide or similar valve material in series relation between a distribution line and ground. Its purpose is to clear the line of abnormal surges and to interrupt the grounded circuit therethrough after the line has been cleared of the abnormal conditions.

Protective apparatus is thus frequently subjected to very severe conditions which damage the valve material and render it inadequate to perform its function as a resistor to the flow of current normally generated in the line and causes lock-out of protective switching equipment.

An object of this invention is to provide an improved circuit interrupting device which will interrupt the flow of current to ground when the protective apparatus fails, but prior to interruption of the line circuit by the protective switching equipment.

The prior art suggests several ways of interrupting grounded circuits through damaged protective apparatus. One which is in wide use is disclosed in the patent to Earle, No. 2,315,320, issued March 30, 1943, for Automatic Circuit Interrupting Devices.

A more specific object of my invention is to provide for a lightning arrester a circuit interrupting device which embodies, in series, an air gap, a fusible joint, and a fuse wire, the arrangement being such that the fusible joint will ordinarily melt, upon failure of the arrester on small fault currents, and the fuse wire will remain intact; while on heavy fault currents the fuse wire will melt before the fusible joint is melted.

Additionally, it is an object to provide a circuit interrupting device for lightning arresters which will introduce a gap between the arrester and ground, will operate independently of ground connections, serves as an indicator of the condition of the arrester, is simple in construction and to assemble, is easily calibrated to function under predetermined conditions, and introduces an arc extinguishing gas into the path of an arc formed by the operation of the interrupting device.

Fig. 1 is a sectional view in side elevation of my interrupter as applied to an arrester.

Fig. 2 is a view similar to Fig. 1, illustrating the arrangement following operation of the interrupter.

Fig. 3 is a sectional view taken on the line 3—3

2

of Fig. 1, showing a cross section of the interrupter.

Fig. 4 is a fragmentary view in vertical section illustrating a modified form of this invention.

- 5 The arrester illustrated in the drawings and more fully described in Patent No. 2,315,320 comprises a housing 1 enclosing an air gap 2 and valve material 3 such as silicon carbide. A conductor 4 extends beneath the housing cap 5 and 10 is electrically connected with the metal closure 6. The lower end of the arrester is provided with an electrode plate 7 having centrally located threaded stud 8 projecting through the bottom of the housing.
- 15 The interrupter comprises a connector cap 9 threaded on the stud and clamping a resilient washer 10 to the bottom of the housing 1, an insulating sleeve 11 threaded into the cap 9 and recessed at 12 beneath the stud 8, a terminal 13 20 threaded on the lower end of the sleeve 11, closure 14 having an insulating guard 15, a link comprising an electrode button 16 seated in the recess 12, a strain wire 17 secured in the recessed end 18 of the button 16 by means of solder 19 and 25 provided with an eye 20 which receives a pin 21 extending transversely through the closure 14. A coil spring 22 embraces the lower portion 23 of the terminal 13 and a portion of the closure 14 and is held under compression between the terminal 30 and closure. Normally the strain wire 17 is held under tension by the spring 22 acting through the closure 14.

- The terminal 13 is provided with a laterally projecting clamping jaw 24 integral therewith, a movable clamping jaw 25 having spaced hook-shaped clamping fingers 26 between which the jaw 24 is positioned, and a clamping bolt 27 threaded through movable jaw 25 and engaging the jaw 24 to draw the fingers 26 into clamping 40 engagement with the ground wire 28. As indicated, the insulating guard 15 is recessed at 29 to accommodate the bolt 27 and jaws 24 and 25 and to give access to the bolt for manipulation thereof.

- 45 In operation, the device functions as follows: When a surge of excessive voltage occurs in a line to which the arrester is connected, it will pass through the conductor 4, across the gap 2, through the valve material 3, across the gap 30 50 between the stud 8 and button 16, and to ground through the wire 17, closure 14, terminal 13, and ground wire 28. A circuit to ground thus established permits generated current in the line to short circuit through the arrester to ground. 55 When the surge current has been dissipated, the

valve material will normally limit the flow of generated current therethrough to a value which will enable the air gap 2 to extinguish the arc therein and interrupt the circuit through the arrester.

However, in the event the valve material 3 is damaged while discharging the excess voltage currents that are passing through it and is then unable to perform its function adequately to restrict the flow of generated currents, the continued flow of a small current across the gap 30 will heat the button 16 sufficiently to melt the solder 19 and release the strain wire 17. In the event a heavy fault current continues to flow across the gap 30, the strain wire 17 will melt. In either event, the coil spring 22 will withdraw the wire 17 by moving the closure 14 and guard 15 downwardly. The closure and guard will continue this movement until they reach a point where they will be held suspended from the terminal 13 by means of the flexible wire 31 more clearly shown in Fig. 2.

As the strain wire 17 or a portion thereof is drawn from the button 16, an arc will be drawn within the bore of the sleeve 11. As indicated, the bore in sleeve 11 may be lined with a gas-evolving material 32, such as fiber, from which an arc extinguishing gas will be evolved by the heat of the arc.

In the event of failure of the arrester, either the interrupter will operate alone to extinguish the arc and interrupt the follow current or the backup fuse on the line will operate to section- 30 alize the arrester before the interrupter extin- 35 guishes the arc. In any event, the blown inter- rupter will always be a visible indication of the failure of the arrester.

Since the movable parts of the interrupter are free, after release, to move without interference by the ground connection, it is obvious that a quick and dependable operation is assured.

In the embodiment disclosed in Fig. 4 the insulating sleeve 35 is threaded into cap 9 and is recessed at 36 beneath the stud 8. An electrode button 37 is seated in the recess 36 and a fusible wire 38 is secured in the recessed end 39 of the button 37 by means of solder 40. Ground wire 41 is joined to the fusible wire 38. The bore of sleeve 35 may be provided with a liner of gas evolving material 42.

The operation of the device disclosed in Fig. 4 is similar to that disclosed for the device illustrated in Fig. 1, except that there is no coil spring to aid in the withdrawal of the ground wire 41 which drops from the sleeve 35 because of gravity and the expulsive force of the gas evolved from the liner 42.

From the foregoing it is apparent that the novel circuit interrupter will protect a line from excessive short circuiting through a damaged arrester, will by proper calibration of its parts in no way interfere with normal operations of the arrester, will serve as an indicator of arrester damage, is simple in construction and to assemble, and may be accurately calibrated to function upon the occurrence of given conditions within the arrester.

I claim:

1. A circuit interrupting device comprising an expulsion tube, a terminal at the upper end of said expulsion tube, a fuse link within said tube, a fusible joint connecting said fuse link and terminal, a closure member supported by said fuse link closing the lower end of said expulsion tube, an electrode spaced from said terminal to

provide a gap therebetween, and spring means biasing said closure member in a direction away from said tube, the arrangement being such that the heat of an arc of predetermined duration, between said terminal and electrode, is operative to sever said fusible joint and release said fuse link and said closure member.

2. A circuit interrupting device comprising in combination an insulating sleeve the inner wall of which embodies an arc extinguishing material, an electrode cap secured to said sleeve and having an electrode portion in alignment with the bore of said sleeve, said sleeve and cap jointly forming an arcing chamber, a fuse link terminal having a flange seated on said sleeve within said arcing chamber and comprising an arcing electrode spaced from said cap, said terminal having a recessed shank in said bore exteriorly of said chamber, a fuse wire in said bore extending from within said recess, and a low melting alloy in said recess securing said fuse wire therein.

3. A circuit interrupting device comprising in combination an insulating sleeve the inner wall of which embodies an arc extinguishing material, an electrode cap secured to said sleeve and having an electrode portion in alignment with the bore of said sleeve, said sleeve and cap jointly forming an arcing chamber, a fuse link terminal having a flange seated on said sleeve within said arcing chamber and comprising an arcing electrode spaced from said cap, said terminal having a recessed shank in said bore exteriorly of said chamber, a fuse wire in said bore extending from within said recess, a low melting alloy in said recess securing said fuse wire therein, and a conductor connected to said fuse wire and extending from said sleeve.

4. A circuit interrupting device comprising in combination an insulating sleeve the inner wall of which embodies an arc extinguishing material, an electrode cap secured to said sleeve and having an electrode portion in alignment with the bore of said sleeve, said sleeve and cap jointly forming an arcing chamber, a fuse link terminal having a flange seated on said sleeve within said arcing chamber and comprising an arcing electrode spaced from said cap, said terminal having a recessed shank in said bore exteriorly of said chamber, a fuse wire in said bore extending from within said recess, a low melting alloy in said recess securing said fuse wire therein, and a closure member at the end of said sleeve opposite said cap, said member secured to said link and being electrically conductive.

5. A circuit interrupting device comprising in combination an insulating sleeve the inner wall of which embodies an arc extinguishing material, an electrode cap secured to said sleeve and having an electrode portion in alignment with the bore of said sleeve, said sleeve and cap jointly forming an arcing chamber, a fuse link terminal having a flange seated on said sleeve within said arcing chamber and comprising an arcing electrode spaced from said cap, said terminal having a recessed shank in said bore exteriorly of said chamber, a fuse wire in said bore extending from within said recess, a low melting alloy in said recess securing said fuse wire therein, a closure member at the end of said sleeve opposite said cap, said member secured to said link and being electrically conductive, and a terminal on said sleeve adjacent said closure member including a conductor clamp electrically connected with said closure member.

6. A circuit interrupting device comprising in

combination an insulating sleeve the inner wall of which embodies an arc extinguishing material, an electrode cap secured to said sleeve and having an electrode portion in alignment with the bore of said sleeve, said sleeve and cap jointly forming an arcing chamber, a fuse link terminal having a flange seated on said sleeve within said arcing chamber and comprising an arcing electrode spaced from said cap, said terminal having a recessed shank in said bore exteriorly 10 of said chamber, a fuse wire in said bore extending from within said recess, a low melting alloy in said recess securing said fuse wire therein, a closure member at the end of said sleeve opposite said cap, said member secured to said link and being electrically conductive, a terminal on said sleeve adjacent said closure member including a conductor clamp electrically connected with said

closure member, and spring means interposed between said closure member and terminal and placing said fuse wire under stress.
